AGITATING DEVICE

William J. O'Leary, Montreal, Quebec, Canada,
assignor to Lucy B. O'Leary, Montreal, Quebec,
Canada

Application May 16, 1934, Serial No. 725,897

10 Claims. (Cl. 74—23)

The present invention relates to agitating devices and more specifically to mixers, beaters, and washing machines.

The object of this invention is to provide an agitating machine for liquids and powders that is simple, durable, efficient, and that can be constructed at low cost without the sacrifice of quality.

Another object of this invention is to provide a simple, economical, and efficient means of translating rotary motion into a combined reciprocating and oscillating motion.

With the above primary and other incidental objects in view, as will more fully appear in the specification, the invention consists of the features of construction, the parts and combinations thereof, and the modes of operation or their equivalents as hereinafter described and set forth in the claims.

20 In the drawing Fig. 1 is a plan view of the device embodying one form of the invention; Fig. 2 is a sectional view taken on the line 2—2. Fig. 3 shows another adaptation of the crank.

The machine comprises a receptacle 3 provided with supporting legs 4 and a hinged cover 5, an agitator 6 secured to a vertical shaft 7, with a crank 8 thereon, which shaft is pivotally secured to the cover 5 by means of the bracket 9, and means for vertical reciprocation and horizontal oscillation of the shaft and agitator.

25 The means for vertically reciprocating and horizontally oscillating the shaft 7 are shown in Figs. 1 and 2, and comprise a shaft 10 disposed at an angle to and out of alignment with shaft 7. The shaft 10 is pivotally secured to the cover by means of bracket 11, and is provided with a crank 12, the throw of which is somewhat less than the throw of crank 8, and with a driving wheel 13 provided with a counterweight 14 on the end opposite 30 the crank.

35 Cranks 8 and 12 are connected with a clevis 15 which is held pivotally connected to crank 8 and held by means of a pin 16 and pivotally and slidably connected to crank 12.

40 The rotation of the shaft 10 will thus cause the shaft 7 and the agitator 6 to be reciprocated vertically and oscillated horizontally simultaneously. The rotation of the shaft 10 is produced by means of an electric motor 17 attached to the bottom of the receptacle 3 and connected by means of a belt 18 to driving wheel 13.

45 The cranks may also be mounted underneath the receptacle, the driven shaft passing up through the bottom of the receptacle and the shafts may be in the same plane if desired. A

spring may be substituted for the counterweight.

While in order to comply with the statute the invention has been described in language more or less specific as to structural features it is understood that the invention is not limited to the specific features shown, but that the means and construction herein disclosed comprise the preferred form of several modes of putting the invention into effect, and the invention is therefore claimed in any of its forms or modifications 10 within the legitimate and valid scope of the appended claims.

Having thus described my invention, I hereby claim:

1. A driving shaft with a portion of its axis offset, the axis of the offset portion being approximately parallel to the axis of the shaft, a driven shaft with a portion of its axis offset, the axis of the offset portion being approximately parallel to the axis of that shaft, the amount of offset of 15 the driven shaft being greater than the amount of offset of the driving shaft, both shafts being pivotally mounted on a base in angular disposition to each other, a connecting link between the offset portions of the axes, said link being 20 pivotally connected to the offset portion of the driven shaft, and pivotally to and slidably on the offset portion of the driving shaft, and means to rotate the driving shaft.

2. A driving shaft with a portion of its axis offset, the axis of the offset portion being approximately parallel to the axis of the shaft, a driven shaft with a portion of its axis offset, the axis of the offset portion being approximately parallel to the axis of that shaft, the amount of offset on the driven shaft being greater than the amount of offset of the driving shaft, both shafts being pivotally mounted on a base in angular disposition to and out of alignment with each other, a connecting link between the offset portions of the axes, said link being pivotally connected to the offset portion of the driven shaft and pivotally to and slidably on the offset portion of the driving shaft, and means to rotate the 30 driving shaft.

3. A horizontal driving shaft with a portion of its axis offset, the axis of the offset portion being approximately parallel to the axis of the shaft, a driven shaft with a portion of its axis offset, the axis of the offset portion being approximately parallel to the axis of that shaft, the amount of offset of the driven shaft being greater than the amount of offset of the driving shaft, both shafts being pivotally mounted on a base in angular disposition to each other, a 35

connecting link between the offset portions of the axes, said link being connected pivotally to the offset portion of the driven shaft, and pivotally to and slidably on the offset portion of the driving shaft, means to rotate the driving shaft and means to equalize the load on the driving shaft.

4. A driving shaft with a portion of its axis offset, the axis of the offset portion being approximately parallel to the axis of the shaft, a driven shaft with a portion of its axis offset, the axis of the offset portion being approximately parallel to the axis of that shaft, the amount of offset of the driven shaft being greater than the amount of offset of the driving shaft, both shafts being pivotally mounted on a base in angular disposition to each other, a connecting link between the offset portions of the axes, said link being connected pivotally to the offset portion of the driven shaft, and pivotally to and slidably on the offset portion of the driving shaft, and electrical means to rotate the driving shaft.

5. A horizontal driving shaft with a portion of its axis offset, the axis of the offset portion being approximately parallel to the axis of the shaft, a driven shaft with a portion of its axis offset, the axis of the offset portion being approximately parallel to the axis of that shaft, the amount of offset of the driven shaft being greater than the amount of offset of the driving shaft, both shafts being pivotally mounted on a base in angular disposition to and out of alignment with each other, a connecting link between the offset portions of the axes, said link being connected pivotally to the offset portion of the driven shaft, and pivotally to and slidably on the offset portion of the driving shaft, means to rotate the driving shaft and means to equalize the load on the driving shaft.

40 6. A driving shaft with a portion of its axis offset, the axis of the offset portion being approximately parallel to the axis of the shaft, a driven shaft with a portion of its axis offset, the axis of the offset portion being approximately parallel to the axis of that shaft, the amount of offset of the driven shaft being greater than the amount of offset of the driving shaft, both shafts being pivotally mounted on a base in angular disposition to and out of alignment with each other, a connecting link between the offset portions of the axes, said link being connected pivotally to the offset portion of the driven shaft, and pivotally to and slidably on the offset portion of the driving shaft, and electrical means to rotate the driving shaft.

7. A horizontal driving shaft with a portion of its axis offset, the axis of the offset portion being approximately parallel to the axis of the shaft, a driven shaft with a portion of its axis offset, the axis of the offset portion being an-

proximately parallel to the axis of that shaft the amount of offset of the driven shaft being greater than the amount of offset of the driving shaft, both shafts being pivotally mounted on a base in angular disposition to and out of alignment with each other, a connecting link between the offset portions of the axes, said link being connected pivotally to the offset portion of the driven shaft, and pivotally to and slidably on the offset portion of the driving shaft, electrical means to rotate the driving shaft and means to equalize the load of the driving shaft.

8. In an agitating device the combination of a receptacle, a driving shaft with a portion of its axis offset, the axis of the offset portion being approximately parallel to the axis of the shaft, a driven shaft with a portion of its axis offset, the axis of the offset portion being approximately parallel to the axis of that shaft, the amount of offset of the driven shaft being greater than the amount of offset of the driving shaft, both shafts being pivotally mounted on the receptacle in angular disposition to each other, a connecting link between the offset portions of the axes, said link being connected pivotally to the offset portion of the driven shaft, and pivotally to and slidably on the offset portion of the driving shaft, and means to rotate the driving shaft.

9. In an agitating device the combination of
a receptacle, a cover, a driving shaft with a
portion of its axis offset, the axis of the offset
portion being approximately parallel to the
axis of the shaft, a driven shaft with a portion
of its axis offset, the axis of the offset portion
being approximately parallel to the axis of that
shaft, the amount of offset of the driven shaft
being greater than the amount of offset of the
driving shaft, both shafts being pivotally mounted
on the cover in angular disposition to each
other, a connecting link between the offset portions
of the axes, said link being connected
pivotally to the offset portion of the driven shaft,
and pivotally to and slidably on the offset portion
of the driving shaft, and means to rotate the driving
shaft. 30. 35. 40. 45.

10. A driving shaft with a portion of its axis offset, the axis of the offset portion being approximately parallel to the axis of the shaft, a driven shaft with a portion of its axis offset, the axis of the offset portion being approximately parallel to the axis of that shaft, the amount of offset of the driven shaft being greater than the amount of offset of the driving shaft, both shafts being pivotally mounted on a base in angular disposition to each other, a clevis connecting the two offset portions of both shafts, and means to rotate the driving shaft. 55
